J. F. RULE,
TYPE WRITING MACHINE,
APPLICATION FILED SEPT. 20, 1913.

1,182,319.

Patented May 9, 1916.

UNITED STATES PATENT OFFICE.

JOHN F. RULE, OF JAMAICA, NEW YORK, ASSIGNOR TO UNDERWOOD TYPEWRITER COMPANY, OF NEW YORK, N. Y., A CORPORATION OF DELAWARE.

TYPE-WRITING MACHINE.

1,182,319.

Specification of Letters Patent.

Patented May 9, 1916.

Application filed September 20, 1913. Serial No. 790,823.

To all whom it may concern:

Be it known that I, JOHN F. RULE, a citizen of the United States, residing in Jamaica, borough of Queens, in the county of 5 Queens and State of New York, have invented certain new and useful Improvements in Type-Writing Machines, of which the following is a specification.

My invention relates to means for indicating and gaging the width of the bottom margin of a work-sheet. In devices of this character it has usually been necessary, in order to set the gage or indicating device for a predetermined margin on the work-sheet, to first mark or indicate on the work-sheet the width of margin desired and then run the sheet through the machine to bring such mark to the printing point, and then set the indicating device or gage accordingly. Such process has to be repeated each time a work-sheet of different length is used. An object of the present invention is to eliminate this indirect and time-consuming method of setting the gage, and to enable 25 the indicator or gage to be adjusted to a work-sheet prior to its insertion in the machine, whereby the indicator may be readily and accurately set for work-sheets of different lengths, and also gaged for a bottom 30 margin of any desired width without any preliminary testing, experimenting or running the work-sheet over the platen.

A support or standard may be removably attached to the paper shelf in rear of the platen, and provided with a ledge or other indicating means for a work-sheet. A carrier in the form of a clamp, slidably mounted on the standard, has pivoted thereto an arm carrying a gage or indicator, which, 40 when said arm is swung upward, may be adjusted to a work-sheet placed on said ledge. The swinging arm is of such length that when again swung downward after being adjusted to a work-sheet, it is automatically brought to proper position to form an indicating stop for the work-sheet when the latter has been run through the machine so that its bottom edge is at or near the printing line. The indicating gage is adjustable to 45 vary the effective length of said arm, and thereby indicate margins of different widths, a scale being provided on the gage enabling the operative to set the same for a margin

of any predetermined or desired width prior to the insertion of the work-sheet in the 55 machine.

Other objects and advantages will hereinafter appear.

In the accompanying drawings, Figure 1 is a sectional elevation view of one form of 60 my invention, adapted and applied to an Underwood typewriting machine. Fig. 2 is a perspective view showing the sliding clamp and pivoted arm carrying the gage. Fig. 3 is a rear fragmentary view showing 65 the means for removably attaching the standard to the machine. Fig. 4 is a front view of the sliding clamp. Fig. 5 is a sectional side elevation of the same. Fig. 6 is a similar view with the clamp released 70 from the standard.

A rotary platen 1 is mounted in a frame having ends 2 connected by a paper shelf 3 at the rear of the platen, said shelf comprising extensions 4 beneath the platen and 75 extending to within a short distance of the printing line. Types 5 strike against the front face of the platen.

In the Underwood typewriting machine the upper edge of the paper shelf 3 is 80 usually curled to form a bead 6, which, together with a brace rod 7 below said bead, is utilized as a holding means for a removable standard 8 on which a margin indicator is mounted. The standard as shown, may 85 comprise a single piece of wire bent at the upper end of the standard to form two parallel rods 9. The lower ends of these rods may be secured in a clamping member 10 of elastic sheet metal, bent to conform to the 90 curvature of the bead 6 and the brace rod 7, said member 10 having an intermediate loop 11 adapted to be sprung in position between said rod 7 and the bead 6 to hold the standard in position. The attachment may 95 thus be quickly removed or replaced on the machine. The form of standard and attaching means therefor, as above described, are not in themselves a part of the present invention.

A spring clamp 12 slidably mounted on the standard 8 forms an adjustable carrier for a margin indicator or gage 13 adjustably mounted in a swinging arm 14 pivoted to the clamp 12. The clamp 12 may be made 105 from a piece of spring sheet metal bent to

form a front plate 15 and a rear plate 16 united by a section provided with an opening 17 through which the rods 9 extend. The lower end of the plate 16 has a forwardly extended offset 18 formed with an opening 19 through which the rods 9 extend. Normally the front and rear portions 15 and 16 of the clamp are sprung apart so as to bind on the rods 9, and thereby 10 frictionally hold the clamp in any position of adjustment. By gripping the clamp between the thumb and finger, the rear plate 16 may be swung forward to the Fig. 6 position, and the clamp thereby released to 15 permit adjustment on the standard 8.

The swinging arm 14 may be formed of a rod offset at one end and bent to form a horizontal pivot for the rod, journaled in ears 20 extending forwardly from the plate 20 15. The arm 14 may have fixed thereto between the ears 20 a square block 21 against which bears a leaf spring 22 on the clamp, and thereby yieldingly holds the arm 14 both in its downwardly extended position, shown 25 in full lines in Fig. 1, and in its upwardly extended position, shown in broken lines in Fig. 1.

On the free end of the arm 14 is a spring clamp or holder 23 in which the indicating 30 gage 13 is adjustably supported. A ledge 24 on which a work-sheet 25 may be supported, as indicated by dotted lines in Fig. 1, when the slide 12 is being adjusted, is 35 preferably located near the lower end of the standard 8, and as shown, is in the form of a tongue stamped out of the support 10 and bent forward. It is to be understood that the primary function of the ledge 24 is to 40 form an indicating or positioning means for one end edge of a work-sheet while the slide 12 is being adjusted to bring the gage 13 to the other end of said sheet, and therefore an indicating mark or other means to indicate a definite position for the lower end of 45 the work-sheet might in some instances take the place of the ledge 24.

The distance between the upper and lower 50 positions of the gage 13 for any given position of the support 12 (assuming the gage 13 to be at its innermost position of adjustment along the arm 14) is substantially equal to the distance from the lower gage or support 24 to the printing line on the platen. The purpose of this relation of parts 55 will more fully appear in connection with the description of the method of operation and use, which is substantially as follows: The gage 13 being moved inwardly along the arm 14 to the position shown in Fig. 1, 60 and said arm 14 being swung up to dotted-line position, the work-sheet 25 is placed with its lower edge on the ledge 24 and the clamp 12 is adjusted to bring the gage 13 to the upper edge of the work-sheet, as shown

in dotted lines in Fig. 1. If, now, the work-sheet is placed in the machine and the gage 13 swung down to the full-line position, Fig. 1, and the work-sheet fed forwardly in the usual manner by rotating the platen, it will be found that the leading edge is brought 70 up to the gage 13, when the bottom edge of the work-sheet is at or near the printing line.

Two methods of adjusting the gage 13 for any predetermined width of bottom margin on the work-sheet, may be used. First, the 75 work-sheet may be positioned as shown in dotted lines, and the gage 13 set, as already described. The gage 13 is then drawn outwardly a distance equal to the desired width of margin on the work-sheet, as for example, 80

one inch, the distance being indicated by a scale 26 on the arm of the gage 13. The work-sheet may now be placed in the machine and the arm 14 swung downwardly, bringing the gage 13 into such position that, 85 when the leading edge of the work-sheet reaches the gage during the operation of the machine, the printing line will be an inch from the bottom margin of the sheet. The second method of using the indicator consists in first drawing the gage 13 outwardly 90

along the arm 14 a distance equal to half the desired width of margin. For example, if an inch margin is desired, the gage 13 is 95 drawn out a half-inch, which is indicated on the scale. The work-sheet is then placed on the ledge 24 and the clamp 12 adjusted to bring the gage 13 to the upper edge of the work-sheet. The latter being removed from the ledge, the arm 14 is swung down, and is thus brought into the same indicating position as in the first described method of adjustment. This second method has the advantage that a wider range of adjustment is 100 permitted with a given range of movement of the gage arm, permitting a comparatively short gage arm to be used. Also, the gage may be adjusted on the swinging arm before the work-sheet is touched. The scale 26 may, if desired, be graduated to line-space 105 distances. For example, the successive markings may be single line-space distances apart; the number of graduations on the scale appearing below the support 23 will thus indicate the width of the bottom margin as measured in double line-space distances. 110

Variations may be resorted to within the scope of the invention, and portions of the improvements may be used without others. 115

Having thus described my invention, I claim:

1. In a typewriting machine, the combination with a rotary platen, of an adjustable indicating device to indicate the arrival at the printing line of a predetermined bottom margin of a work-sheet as it is fed over the platen, and means at the intake 125

side of the platen coöperating with said indicating device to indicate, prior to the introduction of the work-sheet into the machine and independently of a knowledge of the length of the work-sheet, the width of the bottom margin for which said indicating device is adjusted.

2. In a typewriting machine, the combination of a platen, a positioning means for a work-sheet, a gage mounted to swing freely toward and from said positioning means through a distance approximately equal to the distance of said positioning means from the printing line on the platen, and means to automatically stop the gage as it reaches the limit of said movement in either direction and hold it in its stop position.

3. The combination with a rotary platen, of a gage positioned to form a stop for the leading edge of a work-sheet settable to be engaged by said leading edge to indicate when a predetermined bottom margin of the work-sheet has reached the printing point, and means coöperating with said gage to determine, prior to the placing of the work-sheet on the platen, and apart from a knowledge of the length of the work-sheet, the width of said margin for which the gage is set.

4. In a typewriting machine, the combination of a platen, a position-indicator for the end of a work-sheet, a gage, a support on which the gage is mounted, said support adjustable toward and from said position-indicator to position the gage for work-sheets of different lengths, the gage being movable freely relative to its support between definite stop positions while the support is at rest in its adjusted position, the distance between said stop positions being substantially equal to the distance of said position-indicator from the printing line on the platen, and means to automatically stop and hold the gage as it reaches either of said stop positions, the gage being located adjacent to the path of the leading edge of the work-sheet as the latter is fed over the platen and indicating the position of the work-sheet.

5. In a typewriting machine, the combination with a platen, of a support adjustable toward and from the platen, and a gage carried by said support and having a definite range of movement relatively to the said support toward and from the platen, said gage positioned to indicate by the approach of the leading edge of a work-sheet, the nearness of a predetermined bottom margin of the work-sheet to the printing line.

6. The combination with a rotary platen, of a stationary position-indicating means for one edge of a work-piece, a movable

gage having a normal range of swinging movement toward and from the said stationary means substantially equal to the distance of said stationary means from the printing line of the platen, and means to automatically stop the gage when it reaches the limit of said movement in either direction.

7. The combination with a rotary platen, of a stationary position indicator for one edge of a work-piece, said indicator at the intake side of the platen, a swinging arm, and a gage carried thereby and swinging with said arm toward and from said indicator a distance substantially equal to the distance of the said indicator from the printing line on the platen.

8. The combination with a rotary platen, of a stationary position indicator for one edge of a work-piece, said indicator at the intake side of the platen, a swinging arm, a gage carried thereby and swinging with said arm toward and from said indicator a distance substantially equal to the distance of the said indicator from the printing line on the platen, and a support on which said arm is carried, adjustable toward and from said stationary indicator.

9. The combination with a rotary platen, of a stationary position indicator for one edge of a work-piece, said indicator at the intake side of the platen, a swinging arm, a gage carried thereby and swinging with said arm toward and from said indicator a distance substantially equal to the distance of the said indicator from the printing line on the platen, the gage on said arm being adjustable thereon, and a scale to indicate the adjustment of the gage.

10. The combination with a rotary platen, of a stationary position indicator for one edge of a work-piece, said indicator at the intake side of the platen, a swinging arm, a gage carried thereby and swinging with said arm toward and from said indicator a distance substantially equal to the distance of the said indicator from the printing line on the platen, a standard, and a spring clamp adjustable on the standard and forming a support for the swinging arm.

11. The combination with a rotary platen and a paper shelf, of a standard removably attached to said shelf, a support adjustable up and down on the standard, an arm pivoted to said support, a slide on said arm formed with a margin-indicating gage, and a stationary indicator coöperating with said first-named gage.

12. The combination with a rotary platen and a paper shelf, of a standard removably attached to said shelf, a support adjustable up and down on the standard, an arm pivoted to said support, and a slide on said arm formed with a margin-indicating gage.

13. In margin-indicating means, the com-

bination of a slide adjustable to different positions determined by the length of a work-sheet, and a second slide adjustable relatively to the first-named slide to positions corresponding to the desired width of the bottom margin of a work-sheet.

14. In a margin-indicating device, the combination of a supporting member adjustable to positions corresponding to the length 10 of the work-sheet, means to determine said position of adjustment for any work-sheet, and a member carried by said support and adjustable relatively thereto to positions indicating the width of the work-sheet margin.

15. In a margin-indicating device, the combination with a platen, of a supporting member adjustable to positions corresponding to the length of the work-sheet, means to determine said position of adjustment for 20 any work-sheet, and a member carried by said support and adjustable relatively thereto to positions indicating the width of the work-sheet margin, said member being movable after said adjustment into position to 25 form an indicating stop for the work-sheet when the latter has been moved over the platen to bring said margin to the writing line.

16. In a margin-indicating device, the combination of a standard, a support adjustable along the standard, an arm pivoted to the support, and a gage slidable on said arm toward and from its pivot.

17. In a margin-indicating device, the combination of a standard, a support adjustable along the standard, an arm pivoted to the support, a gage slidable on said arm toward and from its pivot, and a scale to indicate the position of the gage relative to 40 said arm.

18. In a margin-indicating device, the combination of a standard, a support adjustable along the standard, an arm pivoted to the support, a gage slidable on said arm toward and from its pivot, said arm movable about its pivot from a position parallel with the standard to a second position parallel with the standard but extending in the opposite direction, and means to hold the arm 50 in said positions.

19. In a typewriting machine, the combination with a rotary platen, of an adjustable bottom margin indicator for a work-sheet on the platen, said indicator comprising a gage mounted on the machine for adjustment, prior to the positioning of the work-sheet on the platen, and independently of a knowledge of the length of the work-sheet, to a position indicated by the work-sheet when the latter is placed in a predetermined position in juxtaposition to the gage, the gage being further adjustable to determine the width of the bottom margin of the work-sheet, and means to indicate the

width of the bottom margin for which the 65 indicator is adjusted.

20. The combination with a rotary platen, of a support adjustable toward and from the platen, a swinging arm carried by said support, and adjustable therewith to positions corresponding to work-pieces of different lengths, and a gage on said arm to indicate by the position of a work-piece relative thereto the nearness of a predetermined bottom margin of the work-piece 75 to the printing line.

21. The combination with a rotary platen, of a support adjustable toward and from the platen, a swinging arm carried by said support and adjustable therewith to positions corresponding to work-pieces of different lengths, and a gage on said arm, to indicate by the position of a work-piece relative thereto, the nearness of a predetermined bottom margin of the work-piece to the 85 printing line, said gage being adjustable on said arm toward and from the platen, to indicate bottom margins of different widths.

22. In a typewriting machine, the combination with a rotary platen, of a bottom 90 margin indicator comprising positioning means for a work-sheet, and a gage adjustable to a position indicated by the work-sheet when the latter is set to said positioning means, said position determined by the 95 length of the work-sheet, said gage mounted on the machine to indicate, by the nearness thereto of the leading edge of said work-sheet as the latter is fed over the platen, the nearness of the printing line to a predetermined bottom margin on said work-sheet. 100

23. The combination with a typewriting machine, of a bottom margin indicating device for work-sheets, comprising an indicator having an adjustment to indicate a 105 bottom margin of any predetermined width, said indicator having a further adjustment to a position indicated by a loose work-sheet used as a gage, said position determined by the length of said work-sheet, and positioning means to determine said gaging position of the work-sheet, said indicator operable when in said position to indicate, as said work-sheet is fed over the platen, the nearness of the printing line to the bottom margin 110 determined by said first-mentioned adjustment of the indicator.

24. The combination with a typewriting machine, of a margin indicating device for the end of a work-sheet, said device comprising an indicator and support therefor, said support adjustable to gage the indicator to a position corresponding to the length of work-sheet to be used, said position determined by means of the loose work-sheet 120 placed in apposition to the said indicator and thereby serving as a gage for the adjustment of said support, said indicator adjustable 125

5 relatively to its support to indicate any desired width of bottom margin, said indicator movable on its support into position to indicate, by means of the nearness thereto of the leading edge of said work-sheet, as the work-sheet is fed over the platen and approaches the indicator, the nearness of the printing

line to the bottom margin for which said indicator is set.
